Application September 22, 1941, Serial No. 411,824

17 Claims. (Cl. 200—6)

My invention relates in general to electrical controls, and has more particular reference to improved switch means, the invention relating more especially to switch mechanism for starting and controlling vapor conduction electric discharge lamps.

An important object of the present invention is to provide compact, inexpensive switch means for controlling the delivery of electrical energy to a device embodying starting means operable during a definite interval in order to aid in initiating operation of the device, such starting means being inactive during the normal operation of the device following the starting period.

Another important object is to provide switch means comprising a pair of switch elements, one of which is in open position while the other is closed, and vice versa, including means to throw the switches operable, in closing one switch and opening the other, to insure that both switch elements may be in closed position during a starting period; a further object being to utilize rotary means for throwing the switches; another object being to employ a pair of oppositely turnable switch members in coaxial alignment; a still further object being to provide manually operable means movable in one direction to throw one switch element and retractable thereafter in another direction to throw the other switch element; yet a further object being to utilize an improved pawl and ratchet construction for actuating the switch elements; and still another object being to utilize a spring-pressed pull chain of simplified construction for actuating switch means.

Another important object is to provide an improved, inexpensive pull-chain connection for switch means, said connection embodying a ferrule universally rockable in a seat formed in the switch assembly, and simplified means for anchoring a flexible pull chain on the ferrule and on the switch mechanism.

Another important object is to provide a simplified and inexpensive rotary switch structure embodying a cam member progressively movable alternately to open and close the switch; a further object being to employ the cam member in combination with a movable switch element in such fashion that the switch element may operate as a latch securing the cam member selectively in switch closed and switch open position; and a further object being to form the switch element as a yieldable blade of conducting material normally urged toward a face of the cam member and adapted to be pressed and held by

the cam member in switch closed position, the cam member being formed when in switch open position to release the blade and permit it to assume switch open position.

5 Another important object resides in providing improved pawl means for actuating a switch operating ratchet; a further object being to form the pawl means as a yoke of resilient material having a pawl-forming arm in position to extend on one side of a ratchet, and a resilient arm adapted to extend at the opposite side of the ratchet and operable normally to urge the pawl into ratchet-engaging position; a further object being to form the yoke as a bent strip of sheet metal; a still further object being to provide a plurality of pawls on said yoke whereby to operate a plurality of ratchets; yet another object being to form said pawls, the one to operate a corresponding ratchet when the yoke is moved in one direction, and the other to operate a corresponding ratchet when the yoke is moved in another direction.

Another important object is to provide simplified means for connecting the yoke with operating means, such as a pull chain; a further object being to provide a connecting link having a head rockably connectible with the yoke as at an opening formed in the medial portions of the yoke-forming strip; a further object being to provide a guide support for the yoke and the yoke connected member and to arrange yielding means in co-operative association with the yoke for urging the same in one direction on said guide.

A further object is to form a yoke guide as a seat for a universally tiltable ferrule; a further object being to provide a simplified link for connecting the yoke with a pull chain anchored in said ferrule.

Another important object is to utilize a friction fitted disk for anchoring a pull chain in a ferrule.

40 Another important object is to provide a switch casing enclosing the switch mechanism, including rivets mounted in and extending through the walls of said casing and having portions exposed outwardly thereof, and to utilize said outwardly exposed rivet portions for the purpose of anchoring and electrically connecting external conductors with the switch means enclosed within said housing.

50 Among the other numerous important objects and advantages of the invention is to provide an unusually neat, compact, rugged and serviceable switch adapted for low cost production; to provide a dual switch of the character mentioned adapted for use in controlling gaseous

conduction lamps and similar devices requiring a main switch and an auxiliary switch operable in a pre-arranged sequence so that the auxiliary switch will be closed and remain closed only during a starting interval, after closure of the main switch, the auxiliary switch being adapted thereafter to open while the main switch remains closed so long as the device continues in operation; to provide a dual switch structure of the character mentioned, wherein the desired sequence of operation of the main and auxiliary switches is accomplished merely by the successive application and release of actuating pressure upon the switch actuating mechanism.

These and numerous other important objects, advantages, and inherent functions of the invention will be fully understood from the following description, which, taken in connection with the accompanying drawings, discloses a preferred embodiment of the invention.

Referring to the drawings:

Figure 1 is a diagrammatic view of a gaseous conduction lamp provided with control means embodying my present invention;

Figure 2 is a perspective view of switch means embodying the present invention;

Figure 3 is an enlarged sectional view taken substantially along the line 3-3 in Figure 2;

Figure 4 is a sectional view taken substantially along the line 4-4 in Figure 3;

Figure 5 is an exploded view of parts forming the device shown in Figures 2, 3 and 4; and

Figure 6 is a sectional view taken substantially along the line 6-6 in Figure 4.

To illustrate my invention, I have shown on the drawings an electrical device 11 adapted to receive electrical energy from a suitable power source 13 through a control device 15, in accordance with my present invention, said control device comprising a main switch 17. Upon closure of the main switch, electrical power for the operation of the device 11 will be delivered thereto through the circuit comprising the conductors 19 and 21. As shown in the drawings, the device 11 comprises a tubular gaseous conduction lamp embodying starting means 23 illustrated as filaments at the opposite ends of the tubular lamp. In starting the lamp in operation, it is necessary to electrically energize the filaments 23 in order to condition the lamp for operation after closure of the switch 17, and consequently the control device 15 embodies an auxiliary switch 25 connected to control the delivery of power to the starting filaments 23. The invention, of course, is not necessarily limited to switch means for the operation and control of gaseous conduction lamps, nor is the invention necessarily restricted in all of its phases to the dual switch arrangement illustrated and described. The several features of the invention, however, are particularly useful when arranged to form the dual switch mechanism, which has great utility when used to control gaseous conduction lamps of the character mentioned.

Application of operating potential between the spaced filaments 23 by closure of the switch 17 will not necessarily start the lamp in operation unless the gaseous medium has been rendered sufficiently conductive to allow current flow thereto between the spaced electrodes 23 at the potential supplied from the source 13. The filaments 23, when energized, function to ionize the gaseous contents of the lamp sufficiently to render the same conducting and thus

condition the lamp for operation. As shown, the conductors 19 and 21 are connected each to one side of a filament 23, a reactance preferably in the form of a choke coil 28 being interposed in the conductor 19 in series with the gaseous conduction path of the lamp. The other side of the filaments 23 are interconnected in series through the auxiliary switch 25 so that when the switches 17 and 25 are both closed, a series circuit may be established, including the power source, the filaments 23, and the switches 17 and 25, whereby thus to energize the filaments and ionize the gaseous contents of the lamp and condition it for operation. After the filaments 23 are energized, the gaseous contents of the lamp become ionized almost instantaneously, and consequently the switch 25 may be opened almost immediately following the closure of the switch 17 and thus disable the filaments 23 after ionizing, because the discharge of electrical power through the gaseous conduction path in the lamp between the electrodes 23 will maintain the ionized electrical conducting condition of the gaseous contents. Furthermore, when the switch 25 is opened, the interruption of the starting circuit imparts an inductive voltage kick by virtue of the coil 28, whereby the lamp goes into operation by virtue of the series circuit, comprising the power source, the conductors 19 and 21, and the conduction path, afforded by the gaseous contents of the lamp in ionized condition through the operation of the filaments 23.

It is an important object of my present invention to provide improved and simplified control mechanism 15, including the main and auxiliary switches 17 and 25, whereby the main switch may be manually operated, as by means of the pull chain 27, to place the switch 17 either in open or in closed position and thus control the delivery of operating power from the source 13 to the device 11 and to operate the auxiliary switch 25 so that it will be in closed position upon the closure of the main switch 17 and will thereafter open to disable the starting means 13 and permit the device 11 to continue in normal operation.

In order to provide a positive, purely mechanical and exceedingly simple and inexpensive mechanism, my present invention contemplates identical structure for the switches 17 and 25 and identical cam members 29 operable to throw the switches to open or closed position, as the case may be, in response to the actuation of the manually operable means 27; and my invention envisages the construction and arrangement of the operating parts in compact form enclosed within a casing 31 from which the operating means 27 projects.

The casing preferably comprises a pair of identical cup-shaped members 33, each having a peripheral wall 35 and an integral bottom wall 37. The members 33 are preferably, though not necessarily, of cylindrical configuration, the bottom wall 37 being circular and having central openings 39 therethrough for the reception of a stem 41 which has opposed riveted ends at the bottoms of the members 33 for securing the same with open ends in facing registration to form a switch casing. The facing edges of the walls of the members 33 are formed with matching cut-out portions 43 forming a circular opening in which is mounted a support fitting 45. The bottom walls of the casing members 33 are formed with openings 47 and 49 on opposite sides of the central

opening 39, and the switches 17 and 25, respectively, comprise rivets 51 fastened in the openings 49 and resilient blades 53 secured on the bottom walls of the members 33 by means of rivets 55 extending in the openings 47. Each blade 53 is thus secured on the bottom of its enclosing member 33 and has a remote portion extending to and overlying the co-operating rivet 51 in the bottom wall of the member 33. To this end, the blade elements 53 preferably comprise resilient sheet material having semi-circular configuration, whereby the free or unanchored end of each member 53 may extend opposite the co-operating rivet 51, the portions of each member 53 opposite the rivet being bent outwardly, as at 57, in a direction away from said co-operating rivet to form a tongue.

Each of the switches 17 and 25 co-operate with one of the cam members 29, which are of identical structure and are mounted on the pin 41 within the casing for rotation about the axis of the pin. Each cam member 29 comprises a hub 59 and a cam portion 61, preferably formed as a disk, extending outwardly of the hub 59. On one side of the disk 61, the hub 59 is preferably cylindrical to fit within the semi-circular blade member 53 of the associated switch. On the opposite side of the disk 61, the hub comprises a ratchet 63. The cam elements 29 and the housing members 33 preferably comprise molded products of hard rubber, Bakelite, or other moldable material.

The face of each cam portion or disk 61 facing away from the ratchet 63 and toward the co-operating switch blade element 53 is formed with a plurality of deep grooves 65 and intermediate tables 67 to successively receive the bent end portion 57 of the co-operating switch blade, the parts being so proportioned that when the blade portion 57 is in engagement with any of the table portions 67, the blade 53 will be forced against the contrary urge of its inherent resilience into electrical contact with the co-operating rivet 51; but when the cam element 29 is in position to receive the blade portion 57 in any one of the deep grooves 65, the blade member 53 will be in switch open position releasing the rivet 51. The elements 29 thus comprise switch actuating cams operable in conjunction with the inherent resilience of the blade members 53 to throw the switches 17 and 25 alternately and successively into switch open and switch closed position.

The switches 17 and 25 may be electrically connected in circuit in simple fashion due to the novel arrangement of the rivets 51 and 55 in the bottom wall of the casing members 23. It will be noted that the outwardly facing ends of the rivets form pockets adapted each to receive a conductor for connecting the switch in circuit. The conductor may easily be soldered in place in the pocket to form neat electrical connection.

It will be noted that the blade portion 57 will co-operate with the associated cam element 29 to permit rotation of the cam in one direction only, that is to say, in the direction toward the free end 57 of the blade. It will be noted also that the members 29 are assembled on the pin 41 with the ratchet portions 63 in adjacent abutting relationship and that the members 29, due to the co-operation of the associated blade elements 53, may turn only in opposite directions on the pin 41.

In order to actuate the cam members 29 alternately to open and close the associated switches, I provide pawl means 69 reciprocal adjacent

the abutting ratchet portions 63 in position to co-operate with said ratchet portions for the turning of the elements 29 in opposite directions on the pin 41, the pawl means being arranged, in the illustrated embodiment, to turn one of the members 29 when moved in one direction and to turn the other member 29 when moved in the opposite direction. To this end, the pawl means 69 comprises a yoke 70 formed preferably from a sheet metal strip and affording a pair of arms 71 and 73 in position extending on opposite sides of the adjacent ratchet portions of the elements 29. The arm 71 is formed to provide a pawl 75 in position to co-operate with one of the ratchet portions 63 and a pawl 77 in position to co-operate with the other ratchet portion 63, the pawl 75 co-operating with the ratchet forming a part of the cam member operatively associated to control the switch 25, and the pawl 77 co-operating with the ratchet forming a part of the cam member operatively associated to control the switch 17. The pawls 75 and 77 are thus arranged on one side of the ratchets 63, and the arm 73 bears upon the opposite sides of said ratchet portions to yieldingly maintain the pawls in operating position with respect to the ratchets. The ratchet portion 63 of each cam member 29 comprises teeth equal in number to the sum of notches 65 and tables 67 in the cam disk 61.

By drawing the yoke 70 radially outwardly of the pin 41, the pawl 77, by co-operation with its associated ratchet portion 63, may turn the cam member controlling the switch 17 from a starting position, in which the end of its associated blade is in switch open position in a deep notch 65, through an angular displacement in clockwise direction, viewing Figure 3, sufficient to register the adjacent table 67 with the end of the switch blade and thus close the switch, or from a starting position with a table 67 engaging the end of the blade and thus closing the switch to a position in which the succeeding notch 65 is opposite the blade, thereby permitting the switch to open. By moving the yoke radially inwardly of the pin 41, the pawl 75, by co-operation with its associated ratchet portion 63, may turn the cam member controlling the switch 25 from a starting position, in which the end of its associated blade is supported in switch closed position on one of the tables 67, through an angular displacement in counter-clockwise direction, viewing Figure 3, sufficient to rotate the cam portion 61 to register the adjacent notch 65 with the end of the switch blade, thereby permitting the switch to open, or from a starting position with the end of the blade in switch open position in a notch 65 to switch closed position with the adjacent table supporting the end of the blade.

It will be noted, therefore, that by initially orienting the members 29 so that the blade of the switch 17 is in a notch 65, that is to say, in switch open position, and with the blade of the switch 25 in position supported on a table 67, that is to say, in closed position, with the switch actuating mechanism in normal retracted position shown in Figure 3, the desired sequence of operation of the switches for controlling the device 11 may be had. With such an arrangement of the cam elements, closure of the switch 17 is accomplished as a result of movement of the yoke 70 in one direction from retracted position, whereby both switches are in closed position while the yoke remains in shifted position, and thereafter the opening of the switch 25 will be caused as a result of the return of the yoke 70 to its normal or

stand-by position. By repeating the cycle of yoke movement, the switch 17 may be opened, followed by closure of the switch 25, which will remain closed until after re-closure of the switch 17 as a result of again repeating the operating cycle of the yoke.

Another switch operating sequence may be provided by orienting the cam devices 29 so that both switch elements 53 are received in cam notches 65 when the yoke is in stand-by position, such arrangement resulting in closure of the switch 17 during the movement of the yoke in one direction followed by closure of the switch 25 during the return movement of the yoke to stand-by position. During a succeeding yoke operating cycle, the switch 17 will be opened, the switch 25 remaining closed during movement of the yoke in one direction, the switch 25 opening as a result of the return of the yoke to normal stand-by position, and the switch 17 remaining open until reclosed by repeating the operating cycle of the yoke.

The present invention includes simple, inexpensive means for actuating the yoke 70, said means being supported by the frame element 45, which preferably comprises a metallic screw machine product of cylindrical configuration having outer screw threaded surfaces 79 and a groove 81 adjacent an end of the element 45. The groove receives the edges of the members 33 defining the opening 43 so that by applying the members 33 upon the grooved end of the member 45, the same is rigidly and firmly secured on the casing in the opening 43. The member 45 is formed with an axial channel 83 opening at the inner end of the fitting into the chamber formed by the casing members 33. Near the outer end of the member 45, the channel 83 is formed with an annular shoulder 85 facing toward the end of the member 45, the channel 83 opening through the shoulder at the outer end of the member 45 through a restricted bore 87 which is surrounded by a rim 89 at the outer end of the member 45 which is formed with a seat 91 outwardly of the rim 89. The medial portions of the yoke 70 extend within the inner end of the channel 83, and said medial yoke portions are connected within the channel 83 with a connecting member 93, which is preferably rockably secured to the yoke. To this end, the medial portions of the yoke may be formed with a slot or opening 95. The connecting member 93 preferably comprises a stem portion 97 and an integral head 99, the same being connected with the yoke by insertion of the stem 97 through the opening 95, and the member 93 preferably comprises a stamped metal piece. The channel 83 of the member 45 serves to support and guide the medial portions of the yoke 70, and the stem of the member 93 extends in the channel 83 and in the bore 87, a spring 101 being arranged in the channel 83 in position encircling the stem of the member 93 and pressing at the opposite ends of the spring upon the shoulder 85 and upon the medial portions of the yoke 70 in order to urge the same normally in a direction radially inwardly toward the pin 41 and the ratchet portions 63. The end of the stem 97 remote from the yoke 70 extends in the bore 87 and is formed for connection with the manually operable means 27 and to this end, as shown in the drawings, is formed with a perforation 103.

The manually operable means 27 preferably comprises a generally cylindrical member which may conveniently be formed as a screw machine

part 105, said part having an axial channel 107 enlarged at one end to form a pocket 109 surrounded by a rim 111 formed for universal rocking engagement on the seat 91. At the end of the fitting 105 remote from the rim 111 is formed a seat 113 surrounded by an annular shoulder 115, the channel 107 opening within the seat 113. In order to connect the member 105 with the connecting member 93, I utilize a chain 117 and a hook 119 preferably comprising a length of stiff wire bent at its midsection to form a pair of spaced arms, the terminal portions of which are formed as hooks. The chain 117 comprises a series of spherical elements 121 of a size freely insertable in the channel 107, the elements 121 being interconnected by links 123 which are rockably secured between adjacent elements 121. The hook member 119 may be attached to the connecting member 93 by drawing the perforated end thereof outwardly of the member 45 and then inserting the hook member in the perforation 103 so that the medial portions of the hook are rockingly received in the perforation. The end element 121 of the chain 117 may then be hung upon the hooked arms of the member 119. Thereupon, the remote end of the chain 117 may be introduced into the cavity 109 in the fitting 105 and threaded thence through the channel 107. The chain may then be fastened on the fitting 105 by means of a holding disk 125 having a radial slot 127 formed therein from an edge to the center of the disk. This disk is applied to the chain between a pair of spherical elements at the outer end of the fitting 105, the slot 127 being just wide enough to receive the intermediate link 123. The disk 125 is press-fitted upon the seat 113 within the rim 115 which, if desired, may be peened over upon the edges of the disk to hold the same in place. The chain 117 may, of course, extend outwardly of the disk 125 to any desired length or may terminate with the spherical chain element 121 which is disposed at the outwardly facing surface of the disk. By rocking the fitting 105 on the seat 91 either by pulling upon the outwardly extending portions of the chain 117 or by directly manipulating the fitting 105, the connecting rod 93 may be drawn outwardly in the channel 83 to compress the spring 101 and thereby draw the yoke 70 from its stand-by position illustrated in Figure 3 against the influence of the spring 101 sufficiently to throw the switch 17 from open to closed position or vice versa. By releasing the manually operable means 27 from tilted position, the spring 101 will reseat the end of the fitting 105 upon the seat 91 and will return the yoke 70 to stand-by position, thereby throwing the switch 25 from open to closed position or vice versa.

The outer threaded surfaces 79 of the member 45 may carry clamping nuts 129 by means of which the switch mechanism may be supported on a panel or frame having a perforation for receiving the member 45 so that by tightening the nuts 129 together upon the member 45 and on opposite sides of the panel, the entire structure may be firmly secured in place.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein dis-

closed being a preferred embodiment for the purpose of illustrating the invention.

The invention is hereby claimed as follows:

1. Switch mechanism comprising a plurality of switches, an actuating cam drivingly associated with each switch, each cam being operable successively to move its associated switch into open and closed position, and common actuating means for the several actuating cams, said common means being manually operable in one direction to actuate one of said cams, spring means to retract said common means in the other direction to actuate another of said cams whereby to move said cams successively in a predetermined sequence in response to manual operation and release of said common means.

2. Switch mechanism comprising a plurality of switches biased toward open position, an actuating cam drivingly associated with each switch, each cam being operable successively to move its associated switch to closed position and to release the switch for opening movement, and common actuating means for the several cams, said common means being manually operable in one direction to actuate one of said cams, spring means to retract said common means in the other direction to actuate another of said cams whereby to move the cams in a predetermined sequence in response to manual operation and release of said common means.

3. Switch mechanism comprising a plurality of switches each comprising a blade movable between switch open and switch closed position and normally biased toward one of said positions, an actuating cam drivingly associated with each blade, each cam being operable successively to move its associated blade against the biasing influence and to release the blade for movement in accordance with its bias, and common actuating means for the several cams, said common means being manually operable in one direction to actuate one of said cams, spring means to retract said common means in the other direction to actuate another of said cams whereby to move the cams successively in a predetermined sequence in response to manual operation and release of said common means.

4. Switch mechanism comprising a plurality of switches each comprising a blade movable between switch open and switch closed position and normally biased toward one of said positions, an actuating cam drivingly associated with each blade, each cam being operable successively to move its associated blade against the biasing influence and to release the blade for movement in accordance with its bias, each cam comprising a member formed with spaced-apart sockets and intermediate tables for successively engaging the co-operating blade in said sockets and on said tables, whereby alternately to project the blade against the biasing influence and allow retraction of the blade under said influence, and common actuating means for the several cams, said common means being operable to move the cams successively in a predetermined sequence.

5. Switch mechanism comprising a plurality of switches each comprising a blade movable between switch open and switch closed position and normally biased toward one of said positions, an actuating cam drivingly associated with each blade, each cam being operable successively to move its associated blade against the biasing influence and to release the blade for movement in accordance with its bias, each cam comprising

a turnable member formed for driving engagement with its associated blade and with ratchet means for turning the same in progressive steps, and common actuating means for the several actuating cams, comprising a movable pawl element formed to successively engage the ratchet means of the several cams whereby to actuate the same in a predetermined sequence.

6. Switch mechanism comprising a plurality of switches each comprising a blade movable between switch open and switch closed position and normally biased toward one of said positions, an actuating cam drivingly associated with each blade, each cam being operable successively to move its associated blade against the biasing influence and to release the blade for movement in accordance with its bias, each cam comprising a turnable member formed for driving engagement with its associated blade and with ratchet means for turning the same in progressive steps, and common actuating means for the several actuating cams, comprising a movable pawl element formed to successively engage the ratchet means of the several cams whereby to actuate the same in a predetermined sequence, the said cams of a pair of switches having the said ratchet means thereof in adjacent relationship and said pawl element including a pawl tine for co-operation with the ratchet means of one cam to turn the same in one direction as the pawl element is moved away from stand-by position and another pawl tine for co-operation with the ratchet means of another cam to turn the same in the opposite direction as the pawl element is returned to stand-by position.

7. Switch mechanism comprising a plurality of switches each comprising a blade movable between switch open and switch closed position and normally biased toward one of said positions, an actuating cam drivingly associated with each blade, each cam being operable successively to move its associated blade against the biasing influence and to release the blade for movement in accordance with its bias, each cam comprising a turnable member formed for driving engagement with its associated blade and with ratchet means for turning the same in progressive steps, and common actuating means for the several actuating cams, comprising a movable pawl element formed to successively engage the ratchet means of the several cams whereby to actuate the same in a predetermined sequence, the said cams of a pair of switches having the said ratchet means thereof in adjacent relationship and said pawl element including a pawl tine for co-operation with the ratchet means of one cam to turn the same in one direction as the pawl element is moved away from stand-by position and another pawl tine for co-operation with the ratchet means of another cam to turn the same in the opposite direction as the pawl element is returned to stand-by position, and yielding means normally urging said pawl element toward stand-by position.

8. Switch mechanism comprising a plurality of switches each comprising a blade movable between switch open and switch closed position and normally biased toward one of said positions, an actuating cam drivingly associated with each blade, each cam being operable successively to move its associated blade against the biasing influence and to release the blade for movement in accordance with its bias, each cam comprising a turnable member formed for driving engagement with its associated blade and with ratchet means

for turning the same in progressive steps, and common actuating means for the several actuating cams, comprising a movable pawl element formed to successively engage the ratchet means of the several cams whereby to actuate the same in a predetermined sequence, the said cams of a pair of switches having the said ratchet means thereof in adjacent relationship and said pawl element including a pawl tine for co-operation with the ratchet means of one cam to turn the same in one direction as the pawl element is moved away from stand-by position and another pawl tine for co-operation with the ratchet means of another cam to turn the same in the opposite direction as the pawl element is returned to stand-by position, yielding means normally urging said pawl element toward stand-by position, and manually operable means for retracting the pawl element from stand-by position against the influence of said yielding means.

9. In switch mechanism the combination with a switch blade movable between switch open and switch closed position, driving means including a reciprocable member for throwing the blade alternately to open and closed positions, spring means normally urging said member in one direction, and manually operable means for retracting the member against the influence of said spring means comprising a tiltable ferrule, of a flexible chain anchored on said ferrule, said chain comprising a series of spaced-apart link elements interconnected by connecting members, said ferrule having a channel receiving a portion of said chain and formed with a shoulder encircling said channel, an anchoring disk having a slot to receive a connecting member of the chain whereby the disk may be assembled on the chain between adjacent link elements thereof in position to bear upon the shoulder of the ferrule in order to anchor the chain against longitudinal movement in one direction on the ferrule, and means to connect the ferrule with said member.

10. In switch mechanism the combination with a switch blade movable between switch open and switch closed position, and operable means for throwing the blade between open and closed positions comprising a rockable ferrule formed with a channel and a shoulder encircling the channel, of a chain extending in the channel and comprising a series of spaced-apart link elements flexibly interconnected by connecting members and an anchoring disk having a slot to receive a connecting member between adjacent links whereby the disk may be attached on the chain in position to engage the shoulder of the ferrule, and means to secure the disk on said shoulder.

11. In switch mechanism the combination with a switch blade movable between switch open and switch closed position, and operable means for throwing the blade between open and closed positions comprising a rockable ferrule formed with a channel and a flange defining a shoulder encircling the channel, of a chain extending in the channel and comprising a series of spaced-apart link elements flexibly interconnected by connecting members and an anchoring disk having a slot to receive a connecting member between adjacent links whereby the disk may be attached on the chain in position to engage the shoulder of the ferrule, said flange and disk being peened together to secure the disk in place.

12. In switch mechanism the combination with a switch blade movable between switch open and switch closed position, and operable means for throwing the blade between open and closed po-

sitions comprising a rockable ferrule formed with a channel and an annular flange defining a shoulder encircling the channel, of a chain extending in the channel and comprising a series of spaced-apart link elements flexibly interconnected by connecting members and an anchoring disk having a slot to receive a connecting member between adjacent links whereby the disk may be attached on the chain in position to engage the shoulder of the ferrule, said disk being swaged to expand the same within the flange to secure the disk in place.

13. In switch mechanism the combination with a switch blade movable between switch open and switch closed position, and operable means for throwing the blade between open and closed positions comprising a rockable ferrule formed with a channel and an annular flange defining a shoulder encircling the channel, of a chain extending in the channel and comprising a series of spaced-apart link elements flexibly interconnected by connecting members and an anchoring disk having a slot to receive a connecting member between adjacent links whereby the disk may be attached on the chain in position to engage the shoulder of the ferrule, said disk being interlockingly secured within said flange to hold the disk in place on said shoulder.

14. The combination with a pair of switches of a switch element rotatable in one direction to alternately open and close one of said switches, another switch element rotatable in the reverse direction to alternately open and close the other of said switches, a ratchet on each of said rotatable switch elements, a reciprocable actuating element having pawl means thereon in position to engage the ratchets on said switch elements whereby to turn one switch element in one direction when said actuating means is projecting in one direction and to turn the other switch element in the reverse direction when said actuating element is retracted in a reverse direction, manually operable means for retracting said actuating element in one direction, and spring means normally biasing said actuating element for projecting movement in the reverse direction whereby to project said actuating element in said reverse direction upon release of said manually operable means.

15. The combination with a pair of switches of a switch element rotatable in one direction to alternately open and close one of said switches, another switch element rotatable in the reverse direction to alternately open and close the other of said switches, a ratchet on each of said rotatable switch elements, a reciprocable actuating element having pawl means thereon in position to engage the ratchets on said switch elements whereby to turn one switch element in one direction when said actuating means is projected in one direction and to turn the other switch element in the reverse direction when said actuating element is retracted in a reverse direction, manually operable means for retracting said actuating element in one direction, and spring means normally biasing said actuating element for projecting movement in the reverse direction whereby to project said actuating element in said reverse direction upon release of said manually operable means, said rotatable switch elements and ratchets thereon comprising identical structures and being mounted for turning movement on a common axis with said ratchets disposed in adjacent side by side relationship.

16. The combination with a pair of switches of a switch element rotatable in one direction to alternately open and close one of said switches, another switch element rotatable in the reverse direction to alternately open and close the other of said switches, a ratchet on each of said rotatable switch elements, a reciprocal actuating element having pawl means thereon in position to engage the ratchets on said switch elements whereby to turn one switch element in one direction when said actuating means is projected in one direction and to turn the other switch element in the reverse direction when said actuating element is retracted in a reverse direction, manually operable means for retracting said actuating element in one direction, and spring means normally biasing said actuating element for projecting movement in the reverse direction whereby to project said actuating element in said reverse direction upon release of said manually operable means, said rotatable switch elements and ratchets thereon being identical structures each comprising a disc and an integral sleeve-like hub forming the ratchet on one side of the disc, said disc on its other side being formed to provide switch operating cam means, said switch elements being supported for turning movement about a common axis with said ratchets disposed in adjacent side by side relationship in position to be actuated by the pawls of said actuating element.

17. The combination with a pair of switches of a switch element rotatable in one direction to alternately open and close one of said switches, another switch element rotatable in

35 the reverse direction to alternately open and close the other of said switches, a ratchet on each of said rotatable switch elements, a reciprocal actuating element having pawl means thereon in position to engage the ratchets on said switch elements whereby to turn one switch element in one direction when said actuating means is projected in one direction and to turn the other switch element in the reverse direction when said actuating element is retracted in a reverse direction, manually operable means for retracting said actuating element in one direction, and spring means normally biasing said actuating element for projecting movement in 10 the reverse direction whereby to project said actuating element in said reverse direction upon release of said manually operable means, said rotatable switch elements and ratchets thereon comprising identical structures and being mounted for turning movement on a common axis with said ratchets disposed in adjacent side by side relationship, said actuating element comprising a member having spaced arms extending on opposite sides of said axis with one arm 15 pressing upon said adjacently disposed ratchets and the other arm formed with a pair of pawl tines in position to cooperate with said ratchets, one tine serving to drive one ratchet in one direction during projecting movement of the actuating element and the other tine being adapted to drive the other ratchet in the reverse direction during retracting movement of said actuating element.

ARTHUR H. BUCKLEY.
